Term of patent 14 years

Int. Cl. D6—01
U.S. Cl. D33—14

FIG. 1 is a perspective view of a combined adjustable table and multiple seat unit in a raised position of use as a drafting table showing my new design;

FIG. 2 is a reduced in scale top plan view thereof;

FIG. 3 is a perspective view similar to FIG. 1 but showing the adjustable table in a lowered position of use as a work table;

FIG. 4 is a reduced in scale top plan view thereof;

FIG. 5 is a side elevation view of the adjustable table as seen in FIG. 4;

FIG. 6 is an end elevation view of the adjustable table in its raised position as seen in FIG. 1; and

FIG. 7 is an end elevation view of the adjustable table in its lowered position as seen in FIG. 3.

The dominant features of my design reside in those portions shown in full lines on the drawing.

This application is a continuation-in-part application of my copending application, Ser. No. D. 8,393 filed Aug. 25, 1967 and now abandoned.

I claim:

The ornamental design for a combined adjustable table and multiple seat unit, substantially as shown and described.
